US00D840107S

(12) **United States Design Patent** (10) **Patent No.:** **US D840,107 S**
(45) **Date of Patent:** ** *Feb. 5, 2019

(54) **COSMETIC PRODUCT CONTAINER**

(71) Applicant: **EOS PRODUCTS, LLC**, New York, NY (US)

(72) Inventors: **Jonathan Teller**, New York, NY (US); **Sanjiv Mehra**, New York, NY (US); **Peter Waxman**, New York, NY (US); **Joseph Speter**, New York, NY (US); **Sherry Jhawar**, New York, NY (US); **Hamish Campbell**, New York, NY (US)

(73) Assignee: **EOS PRODUCTS, LLC**, New York, NY (US)

(*) Notice: This patent is subject to a terminal disclaimer.

(**) Term: **15 Years**

(21) Appl. No.: **29/573,625**

(22) Filed: **Aug. 8, 2016**
